UNITED STATES PATENT OFFICE.

CHARLES E. JENKINS, OF MORGANTOWN, WEST VIRGINIA.

BURIAL-CRYPT.

1,174,867.

Specification of Letters Patent. Patented Mar. 7, 1916.

Application filed May 10, 1915. Serial No. 27,191.

To all whom it may concern:

Be it known that I, CHARLES E. JENKINS, a citizen of the United States, residing at Morgantown, in the county of Monongalia and State of West Virginia, have invented new and useful Improvements in Burial-Crypts, of which the following is a specification.

This invention relates to burial crypts and particularly to that class which are erected above the ground surface, and the primary object of the invention is to provide a crypt wherein the several components are primarily prepared and disposed in the location desired over a hygienic foundation embodying means for purifying the interior of the crypt by thoroughly counteracting and eliminating all deleterious gases and odors and consequently obviating the least objection that might otherwise arise to a surface entombment of a corpse.

A further object of the invention is to provide a crypt comprising essentially a base, an integral body and a gable cover or roof so constructed and proportioned that they may be assembled over a foundation without requiring any particular adjustment, measurement or other devisement to enable the components to be accurately and positively associated and also to provide for an expeditious erection of a crypt having water and air-tight joints.

A further object of the invention is to provide a burial crypt having the parts primarily prepared or constructed at some place of manufacture and capable of being conveyed and readily assembled at a burial location, all of the parts of the crypt being fully cured and presenting hard surfaces and of an ornamental character.

A still further object of the invention is to provide a crypt having a unique form of ventilating means which is so constructed as to permit the air to enter the body thereof but prevent the ingress of insects into the interior of the crypt, and moreover, to provide means in connection with the base for operating with a primarily prepared foundation to thoroughly drain the interior of the crypt of any moisture that may collect therein.

With these and other objects and advantages in view the invention consists in the construction and arrangement of the several parts which will be more fully hereinafter described and claimed.

In the drawings: Figure 1 is a perspective view of a burial crypt embodying the features of the invention. Fig. 2 is a transverse vertical section on the line 2—2, Fig. 60 3. Fig. 3 is a longitudinal vertical section on the line 3—3, Fig. 2. Fig. 4 is a horizontal section taken in the plane of the line 4—4, Fig. 3, and looking in the direction of the arrow. Fig. 5 is a detail perspective 65 view of a preferred form of combined inscription and ventilating plate.

A foundation is first prepared below the ground surface and may be of any depth and consists, first, of a layer 5 of stone, and 70 thereover is placed a layer 6 of lime and charcoal or either one of these materials or other disinfecting material, and after this layer 6 has been properly placed a tile 7 of suitable dimensions is disposed in upright 75 position on the lime and charcoal, as shown by Figs. 2 and 3, said tile being long enough to preferably terminate flush with the top surface of the foundation. Over the layer 6 stone or rubble 8 is filled in the excavation 80 around the tile, and on this stone or rubble is disposed a layer 9 of concrete of such thickness as to bring the same flush with the surface of the ground in which the excavation for the foundation is made. The upper end of the tile 7 also terminates flush with the upper surface of the concrete 9 and the latter is leveled off to receive thereon a base 10 of the crypt. From the foregoing it will 85 be seen that the disinfecting layer or substance is confined between water-proof layers of other material both at the bottom and at the top of the trench or foundation, and as a consequence any deposit coming downwardly through the tile or pipe 7 from the 90 crypt will be retained within the foundation and all gases and liquids will be held against dissemination in the adjacent ground. Moreover, there is no possibility of 95 gases that may be generated and escaping through the pipe or tile 7 when passing into engagement with the disinfecting substance or layer aggregating in a chamber or enclosure from which they might readily leak out and pass through the ground surface 100 and contaminate the atmosphere around and exteriorly of the crypt. This base 10 is reduced at the side and end edges, as at 11 and 12, see Figs. 2 and 3, so as to provide the base 10 with an elevated or thickened 105 intermediate portion, as at 13, which is located within the crypt. The intermediate

enlarged portion 13 of the base 10 is recessed, as at 14, and the said recess gradually inclines in all directions toward a central opening 15 through the base, said opening registering with the upper end of the tile 7 and establishing communication directly with the layer 6 of lime and charcoal or other material. The recess 14 provides for a perfect drainage of the interior of the 10 crypt. The reduced or grooved side and end edge portions of the base 10 form seat means for the lower edge of an integral body 16 which is of substantially rectangular form as shown, but may be varied in contour as 15 desired. The opposite ends 17 of the body are formed with arcuate gables 18, the upper terminals of the sides 19 of the body presenting horizontally flat edges 20, see Fig. 2. The gables 18 intersect at opposite 20 sides with the said top edges 20 of the sides 19 or do not in the least interfere with the full exposure of these upper terminating edges.

The third essential component of the 25 crypt consists of a roof or cover 21 which is preferably of arched form and has opposite ends 22 conforming in contour to the gables 18. The roof or cover 21 at opposite sides is constructed with straight side members 30 23 having depending or overhanging flanges 24, the members 23 also being formed with lower straight edges 25 equal in dimensions to the upper edges 20 of the sides 19 of the body 16. The overhanging flanges 24 depend sufficiently to fully cover and protect the joints at the opposite sides between the upper edges 20 of the body and the corresponding straight edges 25 at the opposite sides of the roof or cover. The ends 22 of 40 the roof or cover are formed with shoulders 26 regularly forming the contour or curvature of said ends and produced by overhanging portions 27, the front overhanging portion being thicker than the rear corresponding 45 portion, as shown by Fig. 3, and projecting a greater distance beyond the adjacent end 17 of the body 16 than does the rear overhanging portion 27 so as to give the crypt a porch or entrance-like appearance 50 at the front end and also to provide for the application of other devices which will be more fully hereinafter explained.

The distance between the shoulders 26 is just equal to the distance between the outer 55 surfaces of the gables 18, and in applying the roof or cover 21 over the body the said gables 18 fit snugly against the shoulders 26 and also have their upper edges bearing against the inner surface of the roof or cover 60 adjacent to said shoulders. Likewise the sides of the roof or cover overhanging the joints between the side portions of the cover and of the body, and not only is a reliable or positive joint means formed between the body and the roof or cover, but 65

the gables coöperating with the shoulders 26 insure an accurate placement of the roof or cover on the body without requiring adjustment, measurement or other setting operations and thereby the assemblage of the roof 70 or cover and the body is facilitated.

The base and body and particularly the body 16 are reinforced or strengthened by introducing therein suitable metal bars, as at 28, the bars 28 in the base 10 having projecting loops 29 arranged as shown. The reinforcing metal bars 28 are embedded in the body 16 and the base 10 at the time the latter parts are formed, and portions of the bars of the base are projected through the 80 top surface of the latter and formed with the loops 29 which are adapted to be engaged by hooks or other devices for conveniently lifting and moving the said base and placing it in position over the foundation. The lowermost bar 28 of the body also has portions thereof inwardly projected in the form of horizontal eyes or loops 30 which are likewise adapted to receive hooks or other engaging means to facilitate the 90 movement and placement of the said body. The body 16 is of such proportions relatively to the thickened or raised intermediate portion 13 of the base that it fits loosely therearound for the formation of a cement 95 joint, the cement being filled in the space 31 between the lower portions of the sides and end walls of the body and the upstanding side and end edges of the said raised intermediate portion of the base, and by this 100 means the joint is concealed. The lower edges of the sides and ends of the body 16 may also be wiped with cement or a thin layer of cement may be introduced between the same and the reduced portions of the 105 base or bottoms of the grooves 12 directly beneath.

A ventilating opening 32 is formed in the front end 17 of the body 16 and thereover is secured a combined inscription and ventilating plate 33 preferably formed of bronze and secured by bolts and nuts 34 engaging openings 35 in diametrically opposite portions of the plate 33 and secured against the inner side of the front end 17. This plate 33 has the inner or rear side formed with a central cavity 36 from which grooves 37 regularly radiate to and through the periphery of the plate, the cavity being applied over the outer terminal of the opening 32 110 and the grooves 37 forming means for the ingress of air to the interior of the crypt. The grooves 37 will be of such dimensions as to practically ventilate the crypt, but will prevent the entrance thereinto of insects and 115 thus obviate the building of nests within the crypt. Any suitable inscription that may be desired may be placed on the outer face of the plate 33.

The roof, cover or cap 21 in accordance 130

with the construction hereinbefore specified provides a hood inclosure at the sides and ends relatively to the portion of the body engaged thereby, and the front greater projection of the hood corresponds to the longer recessed projection 12 at the front end of the base 10, and on this porch extension of the base suitable ornamentations or mementos may be temporarily disposed, such as flowers, potted plants or emblems. At opposite sides of the center the front projected portion of the hood and the side members 23 of the cover have undercut seats 38 to receive the capitals of pillars 40, the bases 41 of said pillars resting upon the extended grooved or recessed portion of the base below. These pillars not only assist in supporting the cover, but give the crypt an ornamental appearance at the front end.

The foundation as hereinbefore described, the base 10 and the body 16 are associated and assembled as shown, and the inclosure having the corpse therein is let down through the open top portion of the body and the bottom of said inclosure bears upon the intermediate raised portion 13 of the base 10 over the opening 15 and the recess 14. The roof, cover or cap 21 is then applied, cement having been first laid on the edges 20 and the edges of the gables 18, and by this means the roof or cover is secured in place and is held against shifting movement by the gables as hereinbefore specified. The columns 40 are then applied, as shown by Fig. 1, it being understood that the capitals and bases of these columns will have cement applied thereto so as to secure them in fixed position.

Owing to the fact that the surface of the entire crypt and especially the roof or cover 21 is hard, it may be suitably carved or provided with emblems as may be desired or other ornamentations.

As hereinbefore explained, the interior of the crypt will be disinfected and all gases or odors eliminated and absorbed by the disinfecting material exposed from the foundation through the tile 7, and, furthermore, all moisture collecting within the crypt will flow down the sides onto the base and into the recess 14 and thence through the tile 7 to the layer of lime and charcoal or other material.

After the parts of the crypt have been sealed as hereinbefore described, a tight structure will be provided, and one of the main advantages is the formation of the base 10, the body 16 and the roof, cover or cap 21 as integral components and whereby the said three essential components may be readily placed in position for use.

It will be understood also that changes in the proportions, dimensions and minor details of the improved crypt may be varied without departing from the spirit of the invention.

What is claimed is:

1. In a device of class specified, a foundation below ground surface and comprising layers of various materials, one of the layers having disinfectant characteristics and disposed between other liquid and gas-proof layers, a tubular device inserted downwardly through a portion of the layers and having its lower end open to the disinfectant layer and its upper end also open and located at the upper portion of the foundation, and a crypt having a base applied on the upper surface of the foundation and formed with an opening communicating with the upper open end of the tubular device.

2. In a device of the class specified, a foundation below ground surface and comprising layers of various materials embodying disinfectant means held between portions of the layers, the latter being liquid-proof and preventing escape of gases to the exterior of the device, a communicating means being provided between the disinfecting means and the ground surface and normally open at said surface, and a crypt having an inclosing body and a base applied on the upper surface of the foundation, the base being provided with an upper recess inclining in all directions and increasing in depth toward an intermediate opening contiguous to said communicating means of the foundation.

3. A crypt of the class specified comprising a base having a recess in its upper side, said recess inclining and increasing in depth 100 equally from the opposite sides and ends toward an intermediate portion thereof where a drain opening at the lowest point of the recess is formed through the base at a distance from both of the side and end 105 edges, a body tightly fitted over and secured to the recessed portion of the base, a cover mounted over the upper portion of the body, and a closed foundation having a central open means communicating with the drain 110 opening in the base, the foundation means preventing the escape of liquids and gases therefrom.

4. A crypt of the class specified comprising a one-piece base, a one-piece body supported on and secured to the base having end portions extending above the horizontal planes of the top side edges thereof, a cover having an overhanging hood at the ends and sides to fit over the upper side edges and the extending end portions of the body, the upper terminals of said extending end portions fitting snugly against the inner sides of the end portions of the hood of the cover and all of the joints between the cover and body concealed by the said hood, the cover having one end materially projected beyond the adjacent end of the body and the base projecting outwardly from the same end of the body a distance equal to that of the 115 120 125 130

cover, and means between the projecting portions of the base and cover to serve as a support for the latter.

5. A crypt of the class specified comprising a base with a recess along the sides and ends, a body having its lower edges engaging the side and end recesses of the base and provided with upper horizontal straight side edges and arcuate end gables projecting above said side edges, the base being longer than the body and continuing integrally beyond one extremity of said body, and an arched cover having a depending hood at the sides and ends thereof to snugly fit over and conceal the side edges and upper edges of the gables, the hood at one end of the cover being longer and projecting outwardly from the adjacent end of the body a greater distance than the hood at the opposite end of the cover, the portion of the hood having the greater projection at one

end of the cover being equal in extent to the portion of the base continuing beyond the same extremity of the body and the opposite lower side portions of the extended portion of the hood having recesses formed therein, the upper edge portions of the body sides and of the gables bearing against the corresponding inner portions of the hood, and supporting means between the continuing portion of the base and the upper extended part of the hood, said supporting means having their upper terminals engaging the said recesses.

In testimony whereof I have hereunto set my hand in presence of two subscribing witnesses.

CHARLES E. JENKINS.
